UNITED STATES PATENT OFFICE.

GEORGE W. BUNNELL, OF WEST MERIDEN, CONNECTICUT, ASSIGNOR TO
C. ROGERS & BROTHERS, OF SAME PLACE.

DESIGN FOR CASKET-HANDLE TIP.

Statement of Trade-Mark No. 6,279, registered July 22, 1873; application filed July 9, 1873.

To all whom it may concern:

Be it known that I, GEORGE W. BUNNELL, of West Meriden, in the county of New Haven and State of Connecticut, have invented a new Design for Casket-Handle Tip; and I do hereby declare the following, when taken in connection with the accompanying drawing and the letters of reference marked thereon, to be a full, clear, and exact description of the same, and which said drawing constitutes part of this specification, and represents a side view.

This invention relates to a design for the tip for the bar of casket-handles and like purposes; and it consists in the peculiar configuration of the tip, as shown in the accompanying illustration.

From the bar A the tip rises slightly, then curves downward, then up to a defined angle, *a*; here a bead, B, is formed, thence terminating in a tip, C, as shown in the accompanying illustration. The surface of the bead is ornamented with lace-work, also, as shown; but this particular ornamentation is not an essential feature of the design.

I claim as my invention—

The design for casket-handle tip, as shown in the accompanying illustration and as herein described, with or without the ornamentation of the bead B.

GEORGE W. BUNNELL.
